UNITED STATES PATENT OFFICE.

THEODORE H. MORRIS AND FRANK T. GRUBBE, OF GARY, INDIANA.

SHADE-HOLDER.

1,299,003.

Patented Apr. 1, 1919.

Application filed June 29, 1918. Serial No. 242,677.

To all whom it may concern:

Be it known that we, THEODORE H. MORRIS and FRANK T. GRUBBE, citizens of the United States, residing at Gary, in the county of Lake and State of Indiana, have invented new and useful Improvements in Shade-Holders, of which the following is a specification.

This invention relates to new and useful improvements in curtain supporters and the principal object of the invention is to provide means for detachably securing the supporters to the window casing by clamping means so as to render the use of screws and the like unnecessary.

Another object of the invention is to provide a device of this character which is simple and durable in construction, reliable and efficient in operation and one which can be manufactured and placed upon the market at a minimum cost.

The invention also consists in certain other features of construction and in the combination and arrangement of the several parts, to be hereinafter fully described, illustrated in the accompanying drawings and specifically pointed out in the appended claims.

In describing our invention in detail, reference will be had to the accompanying drawings wherein like characters denote like or corresponding parts throughout the several views, and in which:—

Figure 1 shows the invention applied to a window.

Fig. 2 is a side view of one of the supporters.

Fig. 3 is a longitudinal section.

Fig. 4 is a detail view.

As shown in these views the invention comprises a pair of supporters adapted to be placed on each side of the window casing for supporting the ends of the curtain pole. Each supporter comprises a screw threaded rod 1 provided with a hand engaging part 2, preferably made in the form of an eagle. 3 indicates a socket for engaging the end of the curtain pole. 4 indicates a sleeve internally screw threaded, to engage the screw threaded rod 1. 5 indicates a pair of clamping members having their ends pivoted to

the sleeve and having their outer ends hooked and the hooks covered with rubber as at 6. 7 indicates a yoke swiveled to the end of the rod 1 and having its ends embracing the clamping members 5. These members are provided with roughened surfaces to prevent the yoke from slipping thereon.

8 is an arm pivoted to the sleeve between the pivotal points of the clamping members and having its outer end provided with a rubber pad 9.

In using the device the hooked ends are engaged with the edges of the casing and said edges clamped on the casing by manipulating the screw threaded rod 1. The arm 8 will engage the face of the casing and act as a brace to support the weight of the curtain.

When it is desired to use portière poles we provide a pair of pivoted fingers 10 located in slots formed in the rod 1. These fingers are adapted to be swung outwardly when in use to receive the portière pole between them. When not in use said fingers are received in the slot and we prefer to have the screw threads in the rod extending over said fingers so that the sleeve may pass over said fingers when necessary.

It is thought from the foregoing description that the advantages and novel features of our invention will be readily apparent.

We desire it to be understood that we may make changes in the construction and in the combination and arrangement of the several parts, provided that such changes fall within the scope of the appended claims.

What we claim is:—

1. A curtain support comprising a pair of members, each consisting of a screw threaded rod, a sleeve thereon, clamping members pivoted to the sleeve and a yoke carried by the rod and engaging said members.

2. A curtain support comprising a pair of members, each consisting of a screw threaded rod, a sleeve thereon, a pair of clamping members pivoted to said sleeve, a yoke swiveled to the rod and engaging said members, and a supporting arm pivoted to the sleeve.

3. A curtain supporter comprising a pair of members, each consisting of a screw threaded rod, a sleeve thereon, a pair of clamping members pivoted to the sleeve, a yoke swiveled to the rod and engaging said members, a supporting arm pivoted to the

sleeve and a pair of pivoted fingers on said rod.

In testimony whereof we affix our signatures.

THEODORE H. MORRIS.
FRANK T. GRUBBE.
